UNITED STATES PATENT OFFICE.

CHARLES F. BERTSCHINGER, OF JAMAICA, NEW YORK, ASSIGNOR OF THREE-FOURTHS
TO TIDE WATER OIL COMPANY, OF BAYONNE, NEW JERSEY, A CORPORATION OF
NEW JERSEY.

ANTIFRAUD MEANS FOR TANKS.

Application filed May 27, 1926. Serial No. 111,942.

The pumps or dispensing stands serving branded gasoline at filling stations are connected with underground tanks of large capacity, the contents of which must be gauged 5 at intervals by means of a rod or stick through a pipe which extends upward from the tank to a box at the ground level. Much fraud has been practised upon the public and the reputable oil companies whose gasoline is sold 10 from these pumps by the filling of the tanks with cheap, inferior fuel. The purpose of this invention is to provide an advantageous filling and gauging means, or in some instances a gauging means alone, which permits 15 such tanks to be gauged, but which prevents, or effectively discourages, unauthorized filling, and which does not require that the gauge rod remain in the tank.

In the accompanying drawings forming 20 part hereof:

Fig. 1 is a view partly in elevation and partly in vertical section of a portion of one of these underground tanks, a gauge and fill pipe rising therefrom, the head on the upper 25 end of the pipe, and the gauge rod inserted, the upper end of the gauge rod being broken away and intermediate portions of the rod and pipe and tank being broken out because of the limits of space;

Fig. 2 is a sectional elevation of the upper 30 end of the pipe and the head thereon, showing the upper opening of said head closed by a plug, which has been removed in Fig. 1;

Fig. 3 is an elevation on a smaller scale 35 showing the tank in the earth, the pipe, and the head in a box at the ground level;

Fig. 4 is a view similar to Fig. 1, showing a modification; and

Fig. 5 is a view similar to Fig. 2, further 40 illustrating this modification.

The drawings illustrate a tank 2 buried in the earth, this tank being the reservoir of a gasoline pump, not shown. Such tanks have capacities ranging from five hundred and 45 fifty gallons to a thousand gallons. A pipe 3 rises from the tank through the ground to a box 4 at the ground level.

In Figs. 1, 2 and 3, a fitting 5 is screwed on the upper end of said pipe, and is sealed 50 against unauthorized removal therefrom, preferably by means of set-screws 6 and a lead seal 7 connecting the screws. The enlarged upper portion 8 of said fitting is provided with an internal screw-thread to receive 55 a removable filling cap 9. This cap is

hollow, contains a broad ball-chamber 10. It may be made in two pieces as shown, permanently and tightly secured together in a suitable manner, or it might be made integral. The flanges 11 and 12 of the filling cap 60 and of the fitting are provided with a suitable number of openings 13, adapted to register and to receive the wire or strap of a lead seal 14, which locks the cap against unauthorized removal, so that the tank may not 65 be filled by any one other than a representative of the proper oil company, who is equipped with means for restoring the seal. A gasket 30 compressed between the cap and the fitting excludes any water that might 70 otherwise seep through the separable screw joint.

The cap 9 has a small opening 15 through its top into the interior of the chamber 10, this opening being provided with a closure 75 16 in the form of a screw plug. The bottom 17 of the chamber slopes downward from all sides to a lower opening 18 directly beneath the opening 15, and this opening is normally guarded by a ball 19, which can, however, be 80 pushed to one side in the chamber, away from the opening 18, as seen in Fig. 1.

In order to fill the tank, the cap 9 containing the ball 19 is removed from the fitting; and after the filling has been accomplished 85 the seal 14 is restored, so that the tank may not be filled thereafter with bootleg gasoline.

The filling station man can, however, measure the contents of the tank by removing the plug 16 and inserting a long gauge rod 90 20 downward from above, through the small openings 15 and 18, the chamber 10 and the pipe 3, into the tank. In so doing, the lower end of the rod, after it has been introduced through the upper opening 15 is manipulated 95 to push the ball to one side, uncovering the opening 18 for its further passage, the chamber being designed to accommodate the ball at one side of the rod, as shown. The rod is then withdrawn, the height of the liquid 100 trace thereon is noted, and the gauging closure 16 is replaced. The opening 15 is too small to admit the end of a hose through which these tanks are filled from drums or tank trucks, and the ball 19 would so close 105 or obstruct any flow of liquid inward and escape of displaced air outward through the openings that it would be impossible to fill the tank in this manner with a large bulk of gasoline without consuming such an excess. 110

sive amount of time and involving so much loss of gasoline through overflow that it would not pay to attempt the fraud upon a tank thus safeguarded.

5 The construction which has been described requires only one pipe and sealing arrangement for both filling and gauging. In some instances a tank may be provided with separate fill and gauge pipes. Figs. 4 and 5 illustrate a construction for such a gauge pipe, which is marked 3^a.

A hollow top 21 is fixed on the upper end of the pipe, where it is sealed by set screws 6 and a seal 7. This top or head contains a ball-chamber 10, like the ball chamber of the other views, having the upper and lower openings 15 and 18, and the sloping bottom 17, the upper opening closable by the plug 16. The structure 21 is shown made in two parts, comprising a fitting 22, which is connected to the pipe 3^a and has the bottom 17 formed in it, and an upper part 23 which is screwed to the lower part against an interposed water-excluding gasket 24. The two parts are sealed together by a seal 25; or the parts might be permanently united, or they might be made integral.

It is an advantage to keep the gauge rod ordinarily out of the tank, since the true reading is not obscured by creepage of the liquid on the rod or by condensation thereon. A wooden stick, if it stands indefinitely in the tank, tends to become saturated with the gasoline, with the result that the apparent depth of liquid shown on the stick may be greater than the actual depth. However, the rod, more particularly a metal rod, could be left in the pipe and tank, if desired, in which event the rod should be short enough so that when resting on the bottom of the tank its upper end would be beneath the closure 16. The ball would be kept at one side of the chamber 10, in readiness to roll down into the seat of the opening 18 as soon as the stick should be withdrawn.

45 It will be understood that there may be various changes in details, without departing from essentials. The ball is an embodiment of an automatic device, or a valve, which guards the gauge rod passage against unauthorized filling through it into the tank, while permitting the insertion of the gauge rod.

55 While the invention is particularly adapted for prevention of fraud in connection with underground tanks, its application to other stationary storage tanks is not excluded.

I claim:

60 1. In combination with an underground tank and a pipe extending upward therefrom, a head on the upper end of said pipe containing a ball chamber having small upper and lower openings forming part of a through way for the insertion of a gauge rod into the tank, a ball in said chamber adapted

70 to guard the lower of said openings which communicates with the pipe, and a gauge rod adapted to pass through said openings and chamber into the pipe and tank, the ball being displaceable by said rod.

75 2. In an underground tank having a pipe extending upward therefrom, a head on the upper end of said pipe containing a ball chamber having small upper and lower openings, means for sealing the head against tampering, and a ball in said chamber guarding the lower of said openings, said openings and chamber forming part of a through way for the insertion of a gauge rod into the tank, said ball being adapted to be displaced by said rod.

80 3. In an underground tank having a pipe extending upward therefrom, a filling closure on the upper end of said pipe, said closure containing a ball chamber having small upper and lower openings, and a ball in said chamber guarding the lower of said openings, said openings and chamber forming part of a through way for the insertion of a gauge rod into the tank, said ball being 85 adapted to be displaced by said rod.

90 4. In a device of the character stated, a closure arranged for attachment to the inlet end of a tank filling pipe, a locking device to prevent removal of said closure, means in 95 said closure forming a restricted passage for the insertion of a rod to measure the contents of the tank to which said filling pipe connects, and valve means comprising a ball normally closing said passage and arranged to 100 be opened by a rod passed through said passage.

95 5. In an underground tank having a pipe extending upward therefrom, the combination of a fitting on the upper end of said pipe, 105 means for securement of said fitting against unauthorized removal from the pipe, a removable filling closure carried by said fitting, means for securement of said closure against unauthorized removal from the fitting, said filling closure containing a ball chamber having small upper and lower openings, and a ball in said chamber guarding the lower of said openings against filling through the closure, said openings and chamber forming part 110 of a through way for the insertion of a gauge rod into the tank, said ball being adapted to 115 be displaced by said rod.

120 6. Anti-fraud means for guarding a gauging entrance to a storage tank, comprising a member applied to the entrance and containing a ball chamber having small upper and lower openings forming part of a through way for the insertion of a gauge rod into the interior of the tank, the lower of said openings affording a ball-valve seat, and a ball 125 guarding said opening against filling, said ball adapted to be pushed aside in the chamber by the insertion of the gauge rod.

130 7. Anti-fraud means for guarding a gaug-

ing entrance to a storage tank, comprising a member applied to the entrance and containing a ball chamber having small upper and lower openings forming part of a through way for the insertion of a gauge rod into the interior of the tank, means for closing the upper of said openings, and a ball in said chamber resting in the lower opening and adapted to guard against filling through said member, said ball adapted to be displaced by the insertion of the gauge rod.

8. Anti-fraud means for guarding the entrance to a storage tank, comprising a member guarding the entrance and containing a ball chamber having small upper and lower openings forming part of a through way for the passage of a gauge rod, means for securing of said member against unauthorized removal, a ball in said chamber adapted to guard the lower of said openings against filling through the member, said ball adapted to be displaced by the gauge rod.

9. Anti-fraud means comprising a fitting adapted to be applied to the fill and gauge entrance of a storage tank, a hollow member carried by said fitting and movable to open the entrance for filling, means for securing of said member against unauthorized opening of the entrance, said member containing a ball chamber having restricted upper and lower openings forming part of a through way for the passage of a gauge rod, and a ball in said chamber guarding the lower of said openings against filling through the member, said ball adapted to be displaced by the gauge rod.

10. Anti-fraud means comprising a fitting adapted to be applied to a fill and gauge en-

trance of a tank, a member carried by said fitting and movable to open the entrance, means for securing of said member against unauthorized opening of the entrance, said member provided with a restricted passage for a gauge rod, and an automatic device carried by said member adapted to guard against fraudulent filling through said passage while permitting the insertion of the gauge rod.

11. In a tank having a gauging entrance, anti-fraud means guarding said entrance, said means affording a restricted passage for the insertion of a gauge rod into the tank and comprising an automatic device adapted to guard against fraudulent filling through said passage while permitting the insertion of the gauge rod.

12. In a device of the character stated, a closure arranged for attachment to the inlet end of a tank filling pipe, a locking device to prevent removal of said closure, means in said closure forming a restricted passage for the insertion of a rod to measure the contents of the tank to which said filling pipe connects, and valve means arranged to close said passage to the flow of liquid.

13. In a device of the character stated, a closure arranged for attachment to the inlet end of a tank filling pipe, a locking device to prevent removal of said closure, means in said closure forming a restricted passage for the insertion of a rod to measure the contents of the tank to which said filling pipe connects, and valve means normally closing said passage and arranged to be opened by a rod passed through said passage.
